DRAFT GEAR

Filed March 14, 1925

Inventor:

Herman C. Priebe

By G. L. Knapp Atty.

UNITED STATES PATENT OFFICE.

HERMAN C. PRIEBE, OF BLUE ISLAND, ILLINOIS.

DRAFT GEAR.

Application filed March 14, 1925. Serial No. 15,623.

My invention relates to railroad car draft gears and particularly to stop lugs employed in conjunction therewith, the invention residing in using these lugs as a means for assembling the center or draft sills and truck bolsters, and also in employing the king pins for uniting opposite stop lugs in unitary structures.

An object of my invention, on the one hand, is to form the lugs separate from one another as proposed in my prior Patent 1,525,885, so that each lug may be riveted to its related sill by power machinery before the lugs are secured together, thereby to assure a most effective, strong and durable union between the lugs and the sills, and to eliminate weaknesses such as invariably occur as a result of manually riveting the lugs to the sills as is necessary by present known methods and means when the lugs are formed integral with one another, and, on the other hand, to provide formations in or on the lugs cooperating with one another when the lugs are assembled together to provide a sleeve for the reception of a king pin such as is usually employed in draft gears of this type for assembling the gear proper with a truck.

In carrying out my invention the opposite stop lugs of a set upon the center or draft sills of a car terminate each in an eye that registers with the terminating eye of the other, the common axis of these eyes being upright and the eyes together constituting a bearing sleeve for the king pin of the adjacent truck bolster. The king pin thus unites the opposite stop lugs in a unitary structure and the stop lugs thus united serve to assemble the car body and truck bolster through the intermediation of the king pin that assembles the lugs.

My invention will be more fully explained by reference to the accompanying drawing in which Fig. 1 is a sectional plan view of a structure made in accordance with the preferred embodiment of the invention; Fig. 2 is a sectional view on line 2-2 of Fig. 1; and Fig. 3 is a sectional view on line 3-3 of Fig. 1.

The center or draft sills 1 and 2 are assembled in any suitable way with the body of the car. The draft gear that is interposed between these sills at each end of a car includes an inner follower 3 and a yoke 4.

Elongated motion limiting stop lugs or cheek plates 5, 6 are riveted to the inner up-

right sides of the center sills at each end of the car and are engaged by the inner end of said follower 3 to limit the inward motion of the follower.

The stop lug 5 has an inwardly projecting wing 7 terminating in an eye 9 and the stop lug 6 has an inwardly projecting wing 8 terminating in an eye 10. These eyes register and their common axis is upright to constitute them a bearing sleeve for the bolster king pin 12, this pin, in turn, serving to unite said stop lugs in a unitary structure.

As illustrated, the center sill structure and the lugs uniting the center sills are also parts of the body bolster which is completed by the addition of wings 13 secured to and projecting laterally and outwardly from the center sills. The truck bolster 14 underlies the body bolster, these two bolsters being respectively provided with the complementary members 15, 16 of a center bearing. The king pin 12 passes through the bearing sleeve composed of the overlapping eyes 9 and 10 and also through upright cylindrical or circular holes in the center bearing members and the truck bolster. The resulting structure is compact and of great strength with a minimum of parts.

Having thus described my invention, I claim:

1. In combination with the draft sills of a car; of a draft gear assembled with said sills; two stop lugs for limiting movement of said draft gear; each sill having a stop lug thereon; said lugs terminating in registering eyes arranged to constitute an upright bearing sleeve; a truck bolster beneath said sills; a center bearing interposed between the sills and truck bolster; and a king pin assembling said truck bolster and center bearing and also passing through the registering eyes of said lugs to assemble the lugs with the truck bolster and center bearing.

2. The combination with the draft sills of a car; of stop lugs carried by said sills, respectively, said lugs being formed separate from one another whereby they may effectively be secured individually to said sills and thereafter secured together to provide a unitary structure, each lug having a portion arranged to overlap a portion of the other lug, and a pin removably engageable through said overlapping portions to secure them together.

3. The combination with the draft sills

- of a car; of stop lugs carried by said sills, respectively, said lugs being formed separate from one another whereby they may effectively be secured individually to said sills
- 5 and thereafter secured together to provide a unitary structure, overlapping eye members carried by said lugs, respectively, and a pin removably engageable through said eye members to secure said lugs together.
- 10 4. As an article of manufacture, a stop lug for use in car draft gears, comprising a member adapted to be secured lengthwise to one of a pair of draft sills, and having a lateral extension shorter than the distance between said sills provided with a king pin receiving opening.
- 15 king pin receiving eye formation adapted to aline with a similar king pin receiving eye formation in a companion lug.
5. As an article of manufacture, a stop lug for car draft gears, comprising a member adapted to be secured lengthwise to one of a pair of draft sills, and having a lateral extension shorter than the distance between said sills provided with a king pin receiving opening.
- 20 In witness whereof, I hereunto subscribe my name.

HERMAN C. PRIEBE.
